US0D1093902S

(12) **United States Design Patent** (10) Patent No.: **US D1,093,902 S**
 Roberts et al. (45) Date of Patent: ** Sep. 23, 2025

(54) **ORGANIZING GRID FOR STORAGE CASE**(71) Applicant: **Magpul Industries Corp.**, Austin, TX (US)(72) Inventors: **Timothy Eric Roberts**, Broomfield, CO (US); **Michael Werner**, Arvada, CO (US); **Clinton Wade Lynch**, Erie, CO (US); **Jacob Blick**, Superior, CO (US); **Kellen Cooper Sansone**, Denver, CO (US)(73) Assignee: **Magpul Industries Corp.**, Austin, TX (US)(***) Term: **15 Years**(21) Appl. No.: **29/849,111**(22) Filed: **Aug. 8, 2022****Related U.S. Application Data**

(63) Continuation of application No. 29/830,445, filed on Mar. 11, 2022, now Pat. No. Des. 1,064,596.

(51) **LOC (15) Cl.** ..... **03-01**(52) **U.S. Cl.**USPC ..... **D3/319**; D9/456(58) **Field of Classification Search**

USPC D3/254-255, 262, 274, 284, 313-314, D3/318-321, 327-328.1; D9/424, 439, D9/456, 756, 759

CLAIM

The ornamental design for an organizing grid for storage case, as shown and described.

DESCRIPTION

FIG. 1 is a left, front, top perspective view of the organizing grid for storage case;

FIG. 2 is a left, front, bottom perspective view of the organizing grid for storage case;

FIG. 3 is a front elevation view of the organizing grid for storage case;

FIG. 4 is a rear elevation view of the organizing grid for storage case;

FIG. 5 is a left elevation view of the organizing grid for storage case;
FIG. 6 is a right elevation view of the organizing grid for storage case;
FIG. 7 is a top view of the organizing grid for storage case;
FIG. 8 is a bottom view of the organizing grid for storage case;
FIG. 9 is a top perspective view of the organizing grid for storage case shown in an environment of use;
FIG. 10 is another top perspective view of the organizing grid for storage case shown in an environment of use;
FIG. 11 is another top perspective view of the organizing grid for storage case shown in an environment of use;
FIG. 12 is a left, front, top perspective view of a second embodiment of the organizing grid for storage case;
FIG. 13 is a left, front, bottom perspective view of the second embodiment of the organizing grid for storage case;
FIG. 14 is a front elevation view of the second embodiment of the organizing grid for storage case;
FIG. 15 is a rear elevation view of the second embodiment of the organizing grid for storage case;
FIG. 16 is a left elevation view of the second embodiment of the organizing grid for storage case;

FIG. 17 is a right elevation view of the second embodiment of the organizing grid for storage case;
FIG. 18 is a top view of the second embodiment of the organizing grid for storage case with a storage case;
FIG. 19 is a bottom view of the second embodiment of the organizing grid for storage case;
FIG. 20 is a top perspective view of the second embodiment of the organizing grid for storage case shown in an environment of use;
FIG. 21 is another top perspective view of the second embodiment of the organizing grid for storage case shown in an environment of use; and,
FIG. 22 is another top perspective view of the second embodiment of the organizing grid for storage case shown in an environment of use.
The evenly dashed broken lines showing a storage case in FIGS. 9-11 and 20-22 depict environment and form no part of the claim. All other evenly dashed broken lines depict portions of the article and form no part of the claim. The dash-dot-dash broken lines depict the bounds of the claimed design.
